CONVERTIBLE WATER HEATING SYSTEM

John Orban, East Orange, N. J.

Application April 11, 1935, Serial No. 15,807

10 Claims. (Cl. 122—20)

This invention relates to an improved convertible water-heating system, viz., a combined furnace-exhaust-heated and gas-burner-heated water-heating unit in an arrangement for supplying hot water under various conditions of weather, environment and modes of utilization; this being similar in some respects to the "Convertible gas and hot flue water-heater" described and shown in my patent application No. 743,695, filed Sept. 12, 1934; but having certain improvements over that apparatus as disclosed herein-after.

One object of this invention is to provide an improved water-heating unit which is seatable on the top of a furnace and attachable to the smoke-outlet member of the furnace and includes an improved form of gas-burner, so that the heating of water by flame (from the gas-burning heater) and by hot fluid (from the furnace) and by heated air (rising from the furnace) can be effected through the heat-conducting medium of water-pipes (or coiled parts) which constitute parts of this water-heating unit.

Another object is to combine said water-heating unit with the same water-supply and circulation-tank that is operatively connected to a separate water heater, and to provide appropriate valved water-conveying pipes so that such heating unit can be used interchangeably with said separate water heater, according to variations of weather, emergencies, etc.

Another object is to provide an appropriate and effective automatic draft-regulating means so as to effect uniformity in heating and to minimize the necessary labor, fuel and consequent expense of operating the system.

Another object is to provide this system with a very simple two-way valve and deflector, as a part of the heating unit, for changing the course of the hot fluid so it will pass from the furnace's outlet member into contact with the water-heating pipe-sections, or will pass by the latter without coming into contact therewith, at will of the user or operator.

Another object is to provide, as a part of the water-heating unit, a longitudinally jointed cross-connecting flue to enable the cross-connecting water-pipe to be attached to the water-heating pipe-sections after the latter are inserted in the heating inlet-flue and heating outlet-flue, thereby to completely enclose the said cross-connecting pipe while providing a continuous hot-fluid-conduit from the inlet end of the emergency flue or valved controlling flue that re-

ceives the smoke or hot fluid from the furnace's outlet member.

Another object is to provide an improved heat-controlled valve-adjusting device for controlling the draught by moving one valve or gate towards the position for opening a cold-air-inlet while moving a second valve or gate towards the position for closing the hot-fluid-air-passage.

Another object is to arrange the water-inlet and water-outlet pipe-sections in reverse relation to the direction of flow through the heating inlet-flue and heating outlet-flue, so that the cool water will first encounter the highest temperature in the water-heater, so the latter imparts maximum heat to the water while minimizing the waste of heat through the exit flue or final disposal flue.

Other objects and important features are pointed out or implied in the following details of description, in connection with the accompanying drawings in which:

Fig. 1 is a perspective view showing the general arrangement of the furnace with its superposed water-heating unit supported in such position that it requires no floor-space, a conventional form of separate water heater, a chimney to which these are connected for inducing a draught therethrough, and a water-tank with its valved pipes and their connections.

Fig. 2 is a view showing the water-heating unit in horizontal section along the line 2—2 of Fig. 1, only a fragment of the furnace and of the heater-supporting frame being shown, and one of the gas-burners or fluid-fuel-burners being omitted.

Fig. 3 is an enlarged detail-assembly view showing how the cross-connecting flue and cross-connection of the water-pipe are constructed and arranged for being assembled without difficulty.

Fig. 4 is an enlarged sectional fragmental detail showing a simple construction and arrangement that can be made to produce satisfactory results and be produced at minimum cost.

Fig. 5 is a fragmental detail showing two coaxial water-heating coils connected by a common type of T-coupling, which may be used instead of the single coil shown in Figs. 2 and 3.

Referring to these drawings, in detail, wherein, similar parts are referred to by similar reference letters and numerals in the several views, the invention is described in detail as follows:

The chimney is shown at C; the liquid or solid fuel furnace, at F; the two gas-burners, at G; the conventional water-heater, at H; the smoke-

pipe of the latter, at P; the water-storage tank, at T; the latter being supplied with a water-supply pipe *ws*, and a service pipe *sp* for conveying hot water to radiators, bath-rooms, and other places and things that need hot water.

The furnace F is provided with a primary smoke-flue *fa* and a secondary smoke-flue consisting of the parts *fb* and *fe*. Removable clean-out caps are shown at *fc*, in several places, and dampers *fd* are indicated on the parts *fa* and *fb* for closing one while opening the other; for instance, when kindling a fire, the smoke-flue *fa* should be open so as to supply a stronger draught and carry off the unconsumed carbon etc., but when the fire has been well kindled and is giving off more heat in proportion to the unconsumed carbon, the damper of the flue-member *fb* should be opened, and the damper to *fa* closed, so the smoke and heated air (hereinafter called hot fluid) will pass through the heating unit HU which is separately shown in detail in Figs. 2, 3, 4 and 5.

The above-mentioned heating unit HU is in the form of an open tubular frame which consists of a valve-controlled flue or by-pass *hb*, an inlet flue *hi*, an outlet flue *ho* and a cross-connecting flue *hc*, the latter being of the knock-down form shown, viz., the part *hcc* having a hinge-joint at *hcf* and securing means at *hcs* here shown as a screw-bolt through apertured flanges of the tubular part *hcc*. By tightening the screws or bolts at *hcs*, the member *hcc* is clamped on the lateral hollow projections *hp* which are primarily free and spaced from one another for a purpose presently explained. The heating unit HU also includes water-heating coils *whc* and a water-coil connection *wcc*. For the purpose of conveniently, economically and properly assembling the water-coils with the water-coil-connection, the latter is made in five parts, viz., two pipe-nipples *pn*, two pipe-couplings *pc* and a pipe-union *pu*, the latter being here shown as a screw-clamp or clamp-band, though any appropriate form of union may be used instead of this form. After the coils are placed in the respective flues *hi* and *ho*, said coils having threaded ends, the cross-conduit *hcc* being removed, the nipples *pn* having the couplings *pc* thereon, the assembling is effected by screwing the couplings *pc* on the ends of the coils so that the free ends of the nipples meet midway between the coils, and then placing and tightening the pipe-union *pu*. Next, the hinged cross-connection *hcc* is placed around the projections *hp*, clamped in place by the securing means *hcs*, and the adjacent ends of the inlet and outlet flues are then closed by means of their closing caps or end-walls *fc*.

While each gas-heater G has some features in common with that shown in the above-mentioned application for patent, it is distinguished by some features that are explained as follows: A gas-distributor *gd* has gas-nozzles *gn* united therewith and provided with needle-valves *nv* for regulating the rate of flow of gas therethrough. For each distributor *gd* there are several gas and air mixing heads *mh* frictionally secured to the respective nipples or nozzles *gn* by a snug taper-fit of each nozzle in a tapered aperture of the correlated mixing head. To each mixing head is secured a distributing pipe *dp* having lateral extensions or gas-jets *gj* united therewith by a tight frictional joint or by other appropriate means. These gas jets extend through jet-ings *jo* of the heating flues *hi* and *ho*, being

loosely fitted therein so as to be removable for cleaning, renewing, etc.; and to prevent accidental displacement of these jets from the jet-openings, an arcuate plate *ap* may be provided with properly spaced openings through which the pipe-plugs *pp* extend into screw-threaded engagement with the pipe-ends that are remote from the aerating or mixing heads *mh*; so it is obvious that the plate *ap* of each gas-burner combines with the correlated gas-distributer *gd* and its nozzles *gn* for securing the gas-burner in effective relation to the correlated heating flue; and in disassembling, the gas-nozzles *gn* are first withdrawn by pulling or hammering or both, the plugs *pp* are removed, and then the distributing pipes can be moved laterally for disconnecting them.

In Figs. 1 and 2, it will be seen that the flue-gate or valve *fd* has two alternative useful positions, the full-line position (Fig. 2) stopping the flow of hot fluid through the flue *hb* and directing the hot fluid through the inlet-flue *hi* from which it passes through the cross-connecting flue *hcc*, thence through the outlet-flue *ho* and back into the flue *hb*; whereas, the broken-line position of the gate *fd* (Fig. 2) closes the inlet flue *hi*, and leaves the by-pass or emergency flue *hp* open, so the hot fluid passes by the heating flues *hi* and *ho*, and these latter flues and their adjuncts can then be cleaned or repaired without interference by the heat or hot fluid.

The outlet end of the valve-controlled flue *hb* is in open communication with a chimney-connecting flue *cf* which may also be called a cold-air-flue, inasmuch as it is provided with an air-inlet *ai* and an air-controlling gate *ag*. A hot gas regulator *hgr* is pivotally supported in the flue *hp* and includes a pivot or axle that carries an arm *a* connected by a link-and-lever arrangement *la* to a thermostat *t* of any appropriate kind and attached to the furnace or to the heating unit HU in any appropriate way; and by this arrangement or combination, the draught is automatically controlled, the gate *hag* being moved to check the flow of hot air, while the gate *ag* is moved to increase the flow of cold air into the chimney, through the cold-air flue *cf*.

Referring again to the heating flues *hi* and *ho*, having the water-heating coils *wha* and *whc* therein, it is seen (in Fig. 1) that each of these flues is provided with an opening or outlet *o* through which an extension *e* of the respective coils adjoins and merges with a water-pipe, the one that connects with the flue *hi* being indicated at *hwp*, being a hot-water-pipe; and the one that connects to the flue *ho* being a cool-water-pipe and indicated at *cwp*. These pipes are connected to the water-tank T in the proper relation, as shown, to effect a circulation of water therethrough and through the coils and their connection *wcc* (Fig. 2); and the direction of flow is indicated by the arrows adjacent to the water pipes *hwp* and *cwp*, this being counter to the direction of flow of the heating fluid through the heating flues, as indicated by the arrows on the latter and on their connection *wcc* (Figs. 1 and 2); so the cool water enters the cooler of the heating flues, viz. the outlet flue *hi*, and the heated water leaves through the hotter of the flues, thus effecting advantages that will be obvious to those familiar with heat-exchange.

A cold-water-pipe *c2* connects the water-heater H to the tank T and is provided with a cut-off valve *v2*; and a hot-water pipe *h2* is connected to the top of the heater H and is connected to the

pipe *hwp*, and thence to the tank *T* through a mutual pipe *mp* which also connects the pipe *hwp* to the tank *T*. Valves *v* and *v1* are interposed in the respective pipes *hwp* and *cwp* for stopping the flow through these pipes when the heater *H* is in use, in mild weather when it is not desirable to use the furnace *F* for heating water. The valves *v2* and *v3* are used to prevent circulation of water through the heater *H* when the heating unit *HU* is in use. However, in extremely cold weather it is possible to use the heater *H* and heating unit *HU* simultaneously, and in combination through the mutual connections *mp* and *T*. A drain-cock *dc* is provided in the cold-water-pipe *cwp*.

It is quite within the scope of this invention to provide any appropriate form of forced draft device in cases where such may be necessary or desirable in lieu of the chimney *C* or in combination therewith.

When a duplex coil or co-axial coils are desirable, in lieu of the single coil of each heating flue, the same may be constructed as shown in Fig. 5 where *e* represents the extension or connection to either pipe *cwp* or *hwp*. An ordinary T-coupling is shown at *t*, and an ordinary union is shown at *u*. The outer coil *oc* is connected to the coupling *t*, and the inner coil *ic* is connected to the union *u*. The opposite end (omitted from the drawings) is constructed the same as here shown in Fig. 5, except that the T-coupling connects to the cross-pipe *wcc* (Fig. 2) instead of to the pipe-section *e*. By superposing the water-heater on the furnace *F*, the dual advantage is attained, of conserving floor-space, and of utilizing the rising heat of the furnace for helping to heat the water-heater.

It is not my intention to limit my patent protection to the precise details of construction and arrangement here shown and specified, for the invention is susceptible of numerous changes within the scope of the inventive ideas as implied and claimed.

What I claim as my invention, is:

1. In a water-heating unit, the combination of a flue having fluid-conducting means at one end portion to attach it to a furnace in open communication with the latter so as to receive hot fluid therefrom and having an outlet for said fluid at its other end portion, a heating inlet-flue disposed in open communication with the first said flue at a point near said fluid-conducting means and having a hollow lateral extension, a water-conducting pipe having a part within said heating inlet-flue and having one end at said hollow lateral extension, a heating outlet-flue disposed in open communication with the first said flue at a point near the said outlet of the latter and having a hollow lateral extension spaced from the first said lateral extension, a second water-conducting pipe having a part within said heating outlet-flue and having one end at said hollow lateral extension of the latter, a tubular water-conducting connection provided with means to secure it to the ends of said pipes and being normally secured thereto and combining therewith to provide a continuous water-passage through said heating inlet-flue and heating outlet-flue, a cross-connecting flue formed with a longitudinal joint that can be opened and spread to permit it to be placed around said water-conducting connection and around the said hollow lateral extensions, said cross-connecting flue being normally fitted around 75 and secured on said hollow lateral extensions

while its longitudinal joint is closed, and means in the first-said flue to deflect hot fluid into said heating inlet-flue.

2. The combination defined by claim 1, the last said means being operable to close said heating inlet-flue and direct all of the said hot fluid through the first said flue and out of effective relation to said water-conducting pipes. 5

3. The combination defined by claim 1, the last said means being movable alternately into position for closing said heating inlet-flue and for closing the first said flue, for purposes specified. 10

4. The combination defined by claim 1, and means to heat the parts of pipe within either said heating inlet-flue or heating outlet-flue either 15 independently of said fluid-conducting means or in addition thereto, at will of the user.

5. The combination defined by claim 1, and means supplemental to said hot fluid for supplying a flame within either the inlet-flue or the 20 outlet-flue and thereby adding to the heat therein.

6. The combination defined by claim 1, and fluid-fuel burning means independent of said furnace and effective for supplying a flame within at least one of said flues so as to consume parts of 25 said hot fluid and thereby minimize the loss of combustible matter while raising the temperature around said parts of water-conducting pipe.

7. The combination defined by claim 1, and means in open communication with said water-conducting pipe to establish a circulation of water therethrough and supply hot water therefrom for utilization. 30

8. The combination of a furnace provided with a flue which has an inlet and an outlet, a heating inlet-flue in open communication with the first said flue at a point near said inlet, a heating outlet flue in open communication with the first said flue at a point near the said outlet, a cross-connecting flue at a distance from the first said flue and in open-communication with said inlet-flue and outlet-flue, a water-tank provided with water-pipes in open communication therewith and extending continuously through said inlet-flue and outlet-flue and cross-connecting flue to 35 provide a continuous water-circulating passage, means independent of said flue to heat the parts of water-conducting pipes that extend through said flues, an exit-flue in open communication with the outlet of the first said flue and having an opening for taking in atmospheric air and provided with a gate for regulating the rate of flow of air through said opening, flow-controlling means within the first said flue and operable to vary the rate of flow of hot fluid from the heating means in the flues that have parts of water-pipes therein, and heat-controlled means to adjust said gate and said flow-controlling means simultaneously. 45

9. The combination of a water-tank, water-pipes in open communication with the water-tank and being united in a proper relation to provide a continuous water-circulating conduit, a furnace having a hollow outlet-member for the exit of hot fluid, a flue in open communication 60 with said outlet member and united therewith for receiving and expelling hot fluid and being provided with apertures arranged therealong, a part of said water-circulating conduit being within said flue, a fluid-fuel burner including nozzles 65 that are arranged along and extend into said flue through said apertures for sustaining a flame therein and therealong so as to raise the temperature by said flame from its own fluid fuel and by consuming products of combustion in said hot 70 flue. 75

fluid from the furnace, and thereby super-heating said part of the water-pipe, the said flue and the contiguous water-pipe and fluid fuel burner being superposed and supported on said furnace so as to conserve floor-space and to receive heat that rises from the top of the furnace, substantially as shown and described.

10. The method of making a water-heating device, consisting in providing a hollow member having a water container therein and also having rows of apertures therealong at opposite sides, providing fuel-conducting tubes each having fuel-conducting jets extending laterally therefrom and also having an apertured aerating element at one 15 end, providing a distributing head having fuel-

conducting nozzles that extend longitudinally substantially parallel to one another, inserting the fuel-conducting jets of each of said tubes simultaneously in the respective rows of apertures by lateral movement of the respective tubes towards said hollow member, and thereafter simultaneously inserting and tightly fitting said nozzles of the distributing head into the apertured aerating elements of said tubes by longitudinal movement of said nozzles in such manner that the nozzles combine with said distributing head and tubes in securing said jets in the apertures of said hollow member.

JOHN ORBAN. 15
